UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

MECHANISM FOR FORMING DOUBLE THREADS UPON THE SOLES OF STOCKINGS MANUFACTURED ON CIRCULAR-KNITTING MACHINES.

SPECIFICATION forming part of Letters Patent No. 761,632, dated May 31, 1904.

Original application filed June 4, 1903, Serial No. 159,996. Divided and this application filed July 17, 1903. Serial No. 165,974.
(No model.)

To all whom it may concern:

Be it known that I, HARRY A. HOUSEMAN, a citizen of the United States, residing at Philadelphia, county of Philadelphia, and State of Pennsylvania, have invented a new and useful Improvement in Mechanism for Forming Double Threads upon the Soles of Stockings Manufactured on Circular-Knitting Machines, of which the following is a full, clear, and exact description, reference being had to the accompanying drawings, which form a part of this specification.

A circular-knitting machine with which my improved mechanism is adapted to be used is clearly shown and described in an application filed by me June 4, 1903, Serial No. 159,996, of which this application is a division. It is therefore not necessary in this application to describe the machine generally. I therefore have in the accompanying drawings and in the following specification illustrated and described specific parts forming the subject of this invention.

In the accompanying drawings, Figure 1 is a partial plan view of needle-cylinder and thread-guide. Fig. 2 is a sectional elevation on line 2 2, Fig. 1. Fig. 3 is an enlarged side detail. Fig. 4 is a side elevation. Fig. 5 is a rear elevation.

30 Q is the ordinary thread-guide.

Q' is the thread-guide for the supplemental thread for the sole. This thread-guide is pivotally attached to the stud q and normally held in active position by the spring q'. This thread-guide has the tailpiece q² resting against the end q³ of the pivoted lever q⁴, said lever having at its opposite end the roller q⁵. Upon the top face of the cam-cylinder F is the raised ledge R, having at one end the inclined face r. The normal position of the roller q⁵ of the lever q⁴ is such that it is within the line of the outer portion of ledge R and the thread-guide Q' under the action of the spring q' in action. When in the operation of the machine the roller q⁵ reaches the face r, it is carried outward to the outer end

of the ledge R, the lever q⁴ turning on its pivot and moving the guide Q' out of action against its spring q'. When the roller q⁵ passes the ledge R, the roller drops from the outer face of the ledge and the spring q' returns it to its original position and the guide Q' into active position. By arranging the position and extent of the ledge R so that it is upon the needle-cylinder at the point where the face of the foot is being formed the supplemental thread will be automatically thrown in and out of action in passing to and from the sole portion of the foot. In order to maintain this guide Q' out of action when those portions of the stocking other than the foot are being formed, I use the following mechanism: The lever q⁴ has the projecting portion s, against which rests the cam s' at the end of the lever S, pivoted in the friction-bearing s². This lever has also the notch r², with which the pin s⁴, acted upon by the spring s⁵, is adapted to drop when the lever S is rocked. By rocking the end of lever S the cam s' acts upon the portion s of lever q⁴, moving the roller q⁵ outward and throwing the thread-guide Q' out of action and the roller q⁵ out of influence of the ledge R, the spring-pin s⁴ acting as an additional holding device. I can operate this lever S automatically by means of the cams T T', which are secured to the pivoted lever T², acted upon by the lever T³, which is vertically movably supported. In the operation of the machine the position of cams T T' is such that the end of lever S passes between them, and by elevating the lever T³ and lever T², so as to bring the cam T' in line with the end of lever S, the lever S is released from the lever q⁴, while if the lever T³ and lever T² be depressed, so that the cam T is in line with the end of lever S, the lever S is operated to move the lever q⁴ to throw the thread-guide out of action. The upward movement of lever T³ may at the appropriate time be given by any desired mechanism. I will now describe one set of mechanism. I use in this machine the same mechanism for operating

the clutch-rod H^8 to shift from rotary motion to reciprocating motion of the cam-cylinder as in the machine of my Patent No. 538,518 and the same mechanism to rotate and reciprocate the cam-cylinder as is set out in my application, filed July 17, 1903, Serial No. 165,973, and it need not here be described in detail. Upon the shaft 200, which determines the operation of such mechanism, I place the cam-roller Z , having the high portion z . Resting upon the roller Z is the roller z' , connected to the part z^2 of the lever T^3 , so that when the shaft is operated on and off the heel and toe of the lever T^3 is raised and depressed and the thread-guide Q' thrown out of and into action. To throw the thread-guide Q' out of action in going on the leg and maintain it out of action during the formation of the leg, I use a pattern-chain Y upon the sprocket Y' on shaft Y^2 . A projecting arm Y^3 from lever T^3 rests upon the pattern-chain. Pivoted to the arm Y^3 so as to be in line with shaft Y^2 is the long arm Y^4 , having the notched end Y^5 . When a high lug Y^6 upon the chain (which is arranged to pass at the time of going on the leg) strikes the end of the arm Y^3 , it lifts the lever T^3 and lever T^2 , moving guide Q' out of action. This movement lifts the arm Y^4 , so that when the lug Y^6 passes it the arm Y^4 drops upon the shaft Y^2 , holding the lever T^3 up and the guide Q' out of action. When the leg has been completed, a side lug Y^8 upon the chain strikes a tailpiece of arm Y^4 , swinging it free from shaft Y^2 and allowing the arm Y^3 to drop and lower the lever T^3 and bring the thread-guide Q' again into action.

In order to prevent the arm Y^4 from acting when the lever T^3 is lifted by the action of cam-roller Z , I use the following mechanism: 100 is a pivoted bar having the pin 101, the bar being in such position that the arm Y^4 will strike the pin 101 before the arm Y^4 alines with shaft Y^2 , so that normally on the lift of the lever T^3 the arm Y^4 is inactive. When the lug Y^6 strikes the lever T^3 , it also lifts the bar 101, so that the arm Y^4 can swing so that the notched portion rests on the shaft. In order to prevent the action of bar 100 and pin 101 when the lug Y^6 lifts the lever T^3 , I construct the bar 100 so that it as well as arm Y^3 is in line with the lug or high link Y^6 , so that in the lifting of the arm Y^3 by the high link the bar is moved, so that the arm Y^4 can swing in line with shaft Y^2 uninfluenced by the bar 100 or pin 101. When the arm Y^4 is in position on the shaft, the pin 101 rests in a detent y^{12} in the arm Y^4 . The bar 100 is released by the lug Y^8 .

Having now fully described my invention, what I claim, and desire to protect by Letters Patent, is—

1. In a circular-knitting machine, in combination, a cam-cylinder, a thread-guide movable in and out of operative position, a pivoted frame to which said cams are secured, a vertically-movable rod upon which said frame is sup-

70 tern-chain, a lug upon the pattern-chain, devices connected with said guide adapted when struck by the lug to move the guide out of operative position, and a second lug on the pattern-chain adapted when it strikes said device to return the guide to its operative position.

2. In a circular-knitting machine, in combination a cam-cylinder, a thread-guide pivoted to the cam-cylinder, a pattern-chain, a lug upon the pattern-chain, devices connected with said guide adapted when struck by the lug to swing the guide upon its pivot out of operative position, and a second lug on the pattern-chain adapted when it strikes said devices to return the guide to its operative position.

3. In a circular-knitting machine, in combination, a cam-cylinder, a thread-guide pivoted thereto, a lever for operating said guide 85 upon its pivot, said operating-lever having a projecting portion, a second pivoted lever, said second lever resting against the operating-lever, and means to tilt said second lever.

4. In a circular-knitting machine, in combination, a cam-cylinder, a thread-guide pivoted thereto, a lever for operating said guide upon its pivot, said operating-lever having a projecting portion, a second pivoted lever, said second lever resting against the operating-lever, means to tilt said second lever, said second lever having a notch, and a spring-pin adapted to enter said notch when said lever is rocked.

5. In a circular-knitting machine, in combination, a thread-guide movable in and out of operative position, an operating-lever for said thread-guide, a second lever, two cams, one of which operates to move said second lever away from the operating-lever and the other cam operating to force said second lever against the operating-lever, and means to move either of said cams in line with said second lever and the other cam out of line.

6. In a circular-knitting machine, in combination, a thread-guide movable in and out of operative position, an operating-lever for said thread-guide, a second lever, two cams, one of which operates to move said second lever away from the operating-lever and the other cam operating to force said second lever against the operating-lever, a pivoted frame to which said cams are secured, a rod upon which said frame is supported and means to move said rod up and down.

7. In a circular-knitting machine, in combination, a thread-guide movable in and out of operative position, an operating-lever for said thread-guide, a second lever, two cams, one of which operates to move said second lever away from the operating-lever and the other cam operating to force said second lever against the operating-lever, a pivoted frame to which said cams are secured, a vertically-movable rod upon which said frame is sup-

ported, a shaft for controlling the shift of the cam-cylinder from rotation to reciprocation and vice versa, a cam-roller having a high portion upon said shaft, a roller resting 5 against said cam-roller, and a connection between said roller and said vertically-movable rod.

8. In a circular-knitting machine, in combination, a cam-cylinder, rotating and reciprocating means for driving said cam-cylinder, a shaft for controlling the shift of the cam-cylinder from rotation to reciprocation and vice versa, a cam-roller, having a high portion, upon said shaft, a vertically-movable 10 lever operated by said cam-roller, a pivoted lever supported upon said last-mentioned lever and cams secured to said last-mentioned lever.

9. In a circular-knitting machine, in combination, a cam-cylinder, rotating and reciprocating means for driving said cam-cylinder, a shaft for controlling the shift of the cam-cylinder-driving means from rotation to reciprocation and vice versa, a cam-roller, having a high portion, upon said shaft, a thread-carrier and connection between said cam and carrier for moving said carrier in and out of action.

10. In a circular-knitting machine, in combination, a cam-cylinder, a thread-guide secured to said cam-cylinder so as to move in and out of action, cams, one adapted to move the guide out of action, the other to move said guide into action, a pivoted lever to which 35 said cams are connected, a vertically-movable lever supporting said first-mentioned lever, an arm projecting from said lever, a pattern-chain, and a lug upon said pattern-chain adapted to strike said arm and lift said last-mentioned lever.

11. In a circular-knitting machine, in combination, a cam-cylinder, a thread-guide secured to said cam-cylinder so as to move it in and out of action, cams, one adapted to move 45 the guide out of action, the other to move said guide into action, a pivoted frame to which said cams are connected, a vertically-movable rod supporting said frame, an arm projecting from said rod, a pattern-chain, a lug upon said 50 pattern-chain adapted to strike said arm and lift said rod, an arm pivoted to the last-mentioned arm, and a shaft, said pivoted arm being in line with said shaft and adapted to drop thereon and hold the vertically-movable rod 55 when the arm to which it is pivoted is moved by the lug.

12. In a circular-knitting machine, in combination, a cam-cylinder, a thread-guide secured to said cam-cylinder so as to move in 60 and out of action, cams, one adapted to move the guide out of action, the other to move said guide into action, a pivoted frame to which 65 said cams are connected, a vertically-movable

rod supporting said frame, an arm projecting from said rod, a pattern-chain, a lug upon 65 said pattern-chain adapted to strike said arm and lift said rod, an arm pivoted to the last-mentioned arm, a shaft, said pivoted arm being in line with said shaft and adapted to drop thereon and hold the vertically-movable rod 70 when the arm to which it is pivoted is moved by the lug, and a second lug upon the pattern-chain adapted to strike said pivoted arm and release it from the shaft.

13. In a circular-knitting machine, in combination, a cam-cylinder, a thread-guide secured to said cam-cylinder so as to move in and out of action, cams, one adapted to move the guide out of action, the other to move said guide into action, a pivoted frame to which 80 said cams are connected, a vertically-movable rod supporting said frame, an arm projecting from said rod, a pattern-chain, a lug upon 85 said pattern-chain adapted to strike said arm and lift said rod, an arm pivoted to the last-mentioned arm, a shaft, said pivoted arm being in line with said shaft and adapted to drop thereon and hold the vertically-movable rod when the arm to which it is pivoted is moved by the lug, and a pivoted bar having a pin, 90 said pin in one position of said bar being in line of movement of said pivoted arm, said pivoted bar being in line of said lug.

14. In a circular-knitting machine, in combination, a cam-cylinder, a thread-guide secured to said cam-cylinder so as to move in and out of action, cams, one adapted to move the guide out of action, the other to move said guide into action, a pivoted frame to which 95 said cams are connected, a vertically-movable rod supporting said frame, an arm projecting from said rod, a pattern-chain, a lug upon 100 said pattern-chain adapted to strike said arm and lift said rod, an arm pivoted to the last-mentioned arm, a shaft, said pivoted arm being in line with said shaft and adapted to drop thereon and hold the vertically-movable rod when the arm to which it is pivoted is moved by the lug, a pivoted bar having a pin, said 105 pin in one position of said bar being in line of movement of said pivoted arm, said pivoted bar being in line of said lug, a detent in said pivoted arm, a pin upon said pivoted bar adapted to rest in said detent when said arm rests upon said shaft and a second lug upon 110 said pattern-chain adapted to simultaneously strike said pivoted arm and pivoted bar disengaging said bar and releasing said arm from 115 said shaft.

In testimony of which invention I have hereunto set my hand, at Philadelphia, on this 15th day of July, 1903.

HARRY A. HOUSEMAN.
